Primary Examiner — Carla Jobe Wright(74) *Attorney, Agent, or Firm* — ScienBiziP, P.C.(57) **CLAIM**

The ornamental design for a case for mobile communications device, as shown and described.

DESCRIPTION

FIG. 1 is a perspective view of a case for mobile communications device showing our design.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a top plan view thereof; and,

FIG. 7 is a bottom plan view thereof.

The broken lines depict portions of the case for mobile communications device that form no part of the claimed design.
